US0D1046119S

(12) **United States Design Patent** (10) **Patent No.:** **US D1,046,119 S**
(45) **Date of Patent:** **** Oct. 8, 2024**

(54) **ENDOSCOPE DISTAL END**

(71) Applicant: **EvoEndo, Inc.**, Englewood, CO (US)

(72) Inventor: **Joel Friedlander**, Englewood, CO (US)

(**) Term: **15 Years**

(21) Appl. No.: **29/805,918**

(22) Filed: **Aug. 31, 2021**

(51) **LOC (14) Cl.** **24-02**

(52) **U.S. Cl.**

USPC **D24/112**; D24/138

(58) **Field of Classification Search**

(57) **CLAIM**

The ornamental design for an endoscope distal end, as shown and described.

DESCRIPTION

FIG. 1 is a front perspective view of a handle assembly showing the new design;

FIG. 2 is a top view thereof;

FIG. 3 is a bottom view thereof;

FIG. 4 is an enlarged back view thereof;

FIG. 5 is an enlarged front view thereof (portions shown in dotted line form no portion of the claimed invention);

FIG. 6 is a side view thereof; and,

FIG. 7 is another side view thereof.

1 Claim, 4 Drawing Sheets
